UNITED STATES PATENT OFFICE

150,330

DESIGN FOR A FILM DEVELOPING HANGER

Alfred H. Atkinson, Minneapolis, Minn.

Application March 6, 1947, Serial No. 137,409

Term of patent 14 years

(Cl. D61—1)

To all whom it may concern:

Be it known that I, Alfred H. Atkinson, a citizen of the United States, residing at Minneapolis, in the county of Hennepin and State of Minnesota, have invented a new, original, and ornamental Design for a Film Developing Hanger, of which the following is a specification, reference being had to the accompanying drawings, forming part thereof.

Figure 1 is a front elevational view of a film developing hanger, showing my new design;

Figure 2 is a side elevational view thereof; and

Figure 3 is a section taken approximately on the line 3—3 of Figure 1.

I claim:

The ornamental design for a film developing hanger, as shown.

ALFRED H. ATKINSON.
